UNITED STATES PATENT OFFICE.

MATHIAS PFATISCHER, OF PHILADELPHIA, PENNSYLVANIA, ASSIGNOR TO ELECTRO DYNAMIC COMPANY, OF NEW YORK, N. Y., A CORPORATION OF PENNSYLVANIA.

DYNAMO-ELECTRIC MACHINE.

No. 870,313.

Specification of Letters Patent.

Patented Nov. 5, 1907.

Application filed July 23, 1906, Serial No. 327,278.

To all whom it may concern:

Be it known that I, MATHIAS PFATISCHER, of Philadelphia, in the State of Pennsylvania, have invented a certain new and useful Improvement in Dynamo-Electric Machines, whereof the following is a specification, reference being had to the accompanying drawings.

The object of my invention is to provide an improved construction and arrangement of the magnetic circuit of the commutating field, in all those types of dynamo-electric machines in which it is advisable or necessary to create an auxiliary magnetic field for the purpose of effecting good commutation. I have illustrated my invention as applied to the type of such machines described in United States Letters Patent No. 775,310, granted to me November 22nd, 1904. It is characteristic of my improved construction that the main polar projections and auxiliary polar projections are respectively included in magnetic circuits which are separate and distinct, the magnetic circuit of said auxiliary projections being formed by the latter in conjunction with the iron of the armature.

My invention comprises the various novel features of construction and arrangement hereinafter more definitely specified.

25 In the drawings, Figure I, is a longitudinal sectional view of a motor conveniently embodying my improvements. Fig. II, is an elevation of the right hand end of said motor as shown in Fig. I, the shaft bearing bracket and parts connected therewith being omitted. Fig. III, is a longitudinal sectional view of a motor, showing a modified form of my invention, wherein the alternate auxiliary polar projections respectively extend from the opposite ends of the coil which energizes them. Fig. IV, is an elevation of the right hand end 35 of the motor shown in Fig. III, the shaft bearing brackets and parts connected therewith being omitted. Fig. V, is a sectional view of a motor, showing a modified form of my invention, wherein the coil which energizes the auxiliary polar projections is rotary and carried by 40 the armature shaft. Fig. VI, is a diagrammatic view showing the wiring connections of a motor conveniently embodying my improvement.

Referring to Figs. I, II and VI, the main field magnet frame 1, is provided with four main field pole pieces or projections 2, and two auxiliary field pole pieces or projections 4, conveniently formed in unitary relation with the auxiliary field magnet frame 5, are disposed at top and bottom of said frame 1, to which they are respectively connected by the plates 6. The armature 50 7, is provided with the shaft 8, and mounted to rotate concentrically with respect to the two series of polar projections 2 and 4, in the bearings 10, in the brackets

11, which are conveniently made separate from said frame 1, and secured to the opposite ends thereof as best shown in Fig. I.

55

The commutator 12, comprises segments respectively connected with the divisional coils 13, of the armature, and is provided with carbon brushes 14 and 15, supported by respective brush holders 16, one of which is indicated in Fig. I. Said brush 14, is connected by 60 the lead 17, with the supply main 18, and said brush 15, is connected by the lead 20, with the single coil 22, whereby the auxiliary polar projections 4, are energized. Said coil 22, is wound on the tubular core 23, which is a hub on the auxiliary field magnet frame 5, in 65 concentric relation with the armature shaft 8, and in axial alinement with the armature, and, is connected by the lead 24, with the other supply main 25.

The rheostat lever 27, is connected by the lead 17, with said supply main 18, in coöperative relation with 70 the contact points 29, and variable resistance coil 30, and, the lead 32, extends from said coil 30, to the coils 33, which are respectively local to the main polar projections, the last one in the series of said coils 33, being connected by the lead 34, with said supply main 25. 75

It may be observed that by the arrangement above described, the coils 33, for the main poles 2, are connected in series relation with each other, but in shunt relation with the armature windings, 13; whereas the coil 22, for the auxiliary poles 4, is connected in series 80 relation with the armature windings 13. The direction of rotation of the armature may be determined by the direction of current through said windings 13, and such direction may be reversed by any suitable switch device; for instance, that indicated at 36, in Fig. VI. 85

The rheostat above described constitutes preferable means for manually varying the strength of the main field of the motor including the polar projections 2, and their coils 33, to weaken said field in correspondence with any desired increase in the number of revolutions of the armature.

In the form of my invention shown in Figs. I and II, the shaft 8, is provided with a fan wheel 38, between the right hand bearing bracket 11, and the coil 22, so that whenever the armature is rotated, air is circulated with respect to said coils 22, and 33, and maintains them at such a temperature as to permit the operation of the motor with a load considerably greater than is permissible with a motor of ordinary construction. However, said air circulating means may be 100 omitted from a motor, otherwise constructed in accordance with my invention, for instance, as indicated in Figs. III, and IV. The arrangement shown in Figs. III and IV, also differs from that shown in Figs. I, and

II, in that whereas, the core 23, of the coil 22, common to the two auxiliary polar projections 4, extends inwardly toward the armature 7, the core 40, extends outwardly with respect to the armature as shown in 5 Fig. III, and, the auxiliary coil 41, which is wound thereon in axial alinement with the armature is common to the four auxiliary polar projections 42, which are disposed in alternate relation with respect to the main polar projections 2, and are supported in concentric relation with the armature shaft 8, by the auxiliary field magnet frame comprising the separable transverse members 43 and 44, as shown in Fig. IV. Moreover, the auxiliary polar projections 4, extend from but one end of the coil 22, and are consequently all of 15 the same polarity, whereas, the auxiliary polar projections 42, extend alternately from opposite ends of the coil 41 and consequently are of respectively alternate polarity; the two projections 42, disposed in vertical position in Figs. III, and IV, in unitary relation 20 with the auxiliary frame member 43, being extended from the inner end of said coil, and the two projections 42, disposed in horizontal position in said figures in unitary relation with the auxiliary frame member 44, being extended from the outer end of said coil. 25 The last described construction is advantageous in that the coil 41, may be readily removed and replaced, said auxiliary frame member 44, which carries the core 40, being detachably secured to the frame member 43 in the position shown, by the bolts 45. Said auxiliary 30 field magnet frame is also detachably secured in concentric relation with the main field magnet frame 1, by the bolts 46, which engage the annular plate 47, as shown in Figs. III and IV.

Although for simplicity of construction it is preferable to have the single coil, which energizes the auxiliary polar projections, in stationary relation with the latter; said coil may be rotary, and may be carried by the armature shaft as indicated in Fig. V. In said figure, the coil 48, which is wound upon the core 49, 35 in unitary relation with the armature core 50, secured upon the armature shaft 8, of course rotates with the armature, but is arranged to energize the auxiliary field magnet frame 51, having the polar projections 52, which are stationary. In the last described arrangement, the coil 48, is included in a circuit established 40 through the slip rings 53, and 54, which are provided with suitable contact brushes.

It may be observed that although in the form of my invention above described wherein all of the auxiliary 45 polar projections are of the same polarity, lines of force in the auxiliary field, local to the armature, extend radially with respect to the armature, and, in the form of my invention wherein the polar projections are of respectively alternate polarity, lines of force 50 of the auxiliary field, local to the armature, extend circumferentially with respect to the latter it is characteristic of all of the forms of my invention above described, that the auxiliary polar projections are energized by a single coil which is disposed in axial 55 alinement with the armature, and that said auxiliary projections are included with the iron of the armature in a magnetic circuit which is separate and distinct from the magnetic circuit including the main polar 60 projections.

Although I prefer to arrange the magnetizing coil 65 of the auxiliary magnetic field as a single coil concentric with the armature shaft, it is to be understood that many of the advantages of my improvement may be attained without that specific construction.

It is to be understood that I do not desire to limit 70 myself to the precise details of construction and arrangement herein set forth as it is obvious that various modifications may be made therein without departing from the essential features of my invention.

I claim:—

1. In a direct current shunt wound motor, the combination with an armature; of a field magnet frame provided with main polar projections; auxiliary polar projections of different cross sectional area, said auxiliary polar projections forming, in conjunction with the armature iron, a 80 magnetic circuit independent of that of the main polar projections; a coil common to said auxiliary poles disposed in axial alinement with the armature; means connecting said main coils in shunt relation to the armature windings; means connecting said auxiliary coil in series relation to the armature windings; and, means arranged to adjustably vary the strength of the current in said shunt coils, independently of said series coil, substantially as set forth.

2. In a direct current shunt wound motor, the combination with an armature; of a field magnet frame provided with main polar projections; auxiliary polar projections of different cross sectional area; coils for said main polar projections; a coil common to said auxiliary polar projections, disposed in axial alinement with the armature; means connecting said main coils in shunt relation to the armature windings; and means connecting said auxiliary coil in series relation to the armature windings, substantially as set forth.

3. In a dynamo electric machine, the combination with 100 an armature; of a field magnet frame supporting a set of main polar projections and a set of auxiliary polar projections in alternate relation with said main polar projections; a set of coils for the main polar projections respectively local thereto in a series surrounding said armature; and, a single coil common to said auxiliary polar projections, disposed in axial alinement with the armature and constituting a compensating winding, substantially as set forth.

4. In a dynamo electric machine, the combination with 110 an armature; of a field magnet frame provided with main polar projections; auxiliary polar projections located between said main polar projections; and, a coil for said auxiliary polar projections, disposed in axial alinement with said armature, substantially as set forth.

5. In a dynamo electric machine, the combination with 115 an armature; of a field magnet frame provided with main polar projections; auxiliary polar projections located between the main polar projections; and, a coil for said auxiliary polar projections, disposed in axial alinement with the armature, substantially as set forth.

6. In a dynamo electric machine, the combination with an armature; of a field magnet frame provided with main polar projections; auxiliary polar projections which are of smaller cross-sectional area and are located between 125 the main polar projections; bearing brackets at the opposite ends of said field magnet frame; a shaft for said armature mounted in said brackets; and, a coil arranged in axial alinement with the armature to energize said auxiliary polar projections, substantially as set forth.

7. In a dynamo electric machine, the combination with an armature; of a field magnet frame having a set of main polar projections; a set of auxiliary polar projections that alternate in position with the main polar projections; a set of main coils respectively local to said 135 main polar projections; and, a single coil common to said auxiliary polar projections, constituting a compensating and regulating winding, substantially as set forth.

8. In a dynamo electric machine, the combination with an armature; of a field magnet frame supporting two sets 140

- of alternately disposed polar projections having windings connected respectively in series and in shunt relation to the armature windings; the windings that are series connected being in axial alignment with the armature, substantially as set forth. 5
9. In a dynamo electric machine, the combination with an armature; of a field magnet frame supporting two sets of alternately disposed polar projections of respectively different cross sectional area and windings connected respectively in series and in shunt relation to the armature windings, the series connected windings being in axial alignment with the armature, substantially as set forth. 10
10. In a dynamo electric machine, the combination with an armature; of a field magnet frame having a set of main 15 polar projections; a set of auxiliary polar projections that alternate in position with the main polar projection; a set of main coils respectively local to said main polar projections; a single coil common to said auxiliary polar projections, constituting a compensating winding, said alternate auxiliary polar projections extending respectively from opposite ends of said single coil, substantially as set forth. 20
11. In a dynamo electric machine, the combination with an armature; of a field magnet frame provided with main 25 polar projections; auxiliary polar projections located between said main polar projections; and, a single coil common to said auxiliary polar projections; said auxiliary polar projections extending alternately from opposite ends of said coil, substantially as set forth. 30
12. In a dynamo electric machine, the combination with a rotary armature; of a stationary field magnet frame provided with stationary main polar projections; stationary auxiliary projections, forming in conjunction with the armature iron, a magnetic circuit distinct from that of the main polar projections; and, a coil disposed in axial alignment with said armature, arranged to energize said auxiliary polar projections, substantially as set forth. 35
13. In a dynamo electric machine, the combination with an armature; of a main field comprising coils provided 40 with main polar projections; an auxiliary field comprising a coil provided with auxiliary polar projections extending alternately from the respectively opposite ends thereof, and between said main polar projections, substantially as set forth. 45
14. In a dynamo electric machine, the combination with an armature; of a main field comprising coils provided with main polar projections; an auxiliary field comprising a coil provided with auxiliary projections extending alternately from the respectively opposite ends thereof, and between said main polar projections; said auxiliary field 50 coil being disposed in axial alignment with said armature, substantially as set forth.
15. In a dynamo electric machine, the combination with an armature; of a main field comprising coils provided 55 with main polar projections; an auxiliary field comprising a coil provided with auxiliary polar projections extending between said main polar projections; said auxiliary polar projections being of respectively alternate polarity, substantially as set forth.
16. In a dynamo electric machine, the combination with an armature; of a main field comprising coils provided with main polar projections; an auxiliary field comprising a coil provided with auxiliary polar projections extending between said main polar projections; said auxiliary polar 60 projections being of respectively alternate polarity, and equal in number to said main polar projections, substantially as set forth.
17. In a dynamo electric machine, the combination with an armature; of a main field comprising coils provided 65 with main polar projections; an auxiliary field comprising a coil provided with auxiliary polar projections extending between said main polar projections; said auxiliary polar projections being of respectively alternate polarity; whereby lines of force of said auxiliary field local to the armature, extend circumferentially with respect to the armature axis, substantially as set forth. 70
18. In a dynamo electric machine, the combination with an armature; of a main field comprising coils provided 75 with main polar projections; an auxiliary field comprising
- with main polar projections; an auxiliary field comprising a coil provided with auxiliary polar projections, extending between said main polar projections; said auxiliary coil being disposed in concentric relation with said armature, substantially as set forth. 80
19. In a dynamo electric machine, the combination with an armature having a shaft; of a main field magnet frame 85 provided with polar projections; an auxiliary field magnet frame comprising a central hub encircling said armature shaft; polar projections extending outwardly from said hub within said main frame and between said main polar projections; and, means detachably securing said main field frame and auxiliary field frame in concentric relation, substantially as set forth. 90
20. In a dynamo electric machine, the combination with an armature having a shaft; of a main field magnet frame provided with polar projections; an auxiliary field magnet frame comprising a central hub encircling said armature shaft; polar projections extending outwardly from said hub within said main frame and between said main polar projections; and, means detachably securing said main field frame and auxiliary field frame in concentric relation, substantially as set forth. 95
21. In a dynamo electric machine, the combination with an armature having a shaft; of a main field magnet frame provided with polar projections; an auxiliary field magnet frame provided with polar projections extending within 100 said main frame between said main polar projections; and, means securing said main field frame and auxiliary field frame in concentric relation, comprising an annular plate detachably connected with both of said frames, substantially as set forth. 110
22. In a dynamo electric machine, the combination with an armature having a shaft; of a main field magnet frame provided with polar projections; an auxiliary field magnet frame provided with polar projections extending within 115 said main frame between said main polar projections; and, means securing said main field frame and auxiliary field frame in concentric relation, comprising a plate detachably connected with both of said frames, substantially as set forth. 115
23. In a dynamo electric machine, the combination with an armature having a shaft; of a main field magnet frame provided with polar projections; an auxiliary field magnet frame distinct from said main frame and comprising separable members, extending transversely with respect to said shaft, carrying auxiliary polar projections; and, means detachably securing said auxiliary frame members in separable relation, substantially as set forth. 120
24. In a dynamo electric machine, the combination with an armature having a shaft; of a main field magnet frame provided with polar projections; an auxiliary field magnet 130 frame distinct from said main frame and comprising separable members, extending transversely with respect to said shaft, carrying auxiliary polar projections; and, a coil between said frame members arranged to energize said auxiliary polar projections, substantially as set forth. 130
25. A dynamo electric machine having an armature, main field polar projections and auxiliary commutating-field polar projections; the axes of said main polar projections being radial with respect to the armature axis, and the axes of said auxiliary polar projections being parallel with the armature axis; and, a coil arranged with its axis parallel with the axis of the armature to energize said auxiliary polar projections, substantially as set forth. 135
26. A dynamo electric machine having an armature, main field polar projections and auxiliary commutating-field polar projections; the axes of said main polar projections being radial with respect to the armature axis, and the axes of said auxiliary polar projections being parallel with the armature axis; a main field frame rigidly connecting said main polar projections independently of said auxiliary polar projections; and, an auxiliary field frame rigidly connecting said auxiliary polar projections independently of said main polar projections, substantially as set forth. 140
27. A dynamo electric machine having an armature, main field polar projections and auxiliary commutating-field polar projections; and, a coil arranged with its axis 150

parallel with the axis of the armature to energize said commutating-field polar projections, substantially as set forth.

28. In a dynamo electric machine, the combination with 5 a rotary armature; of a stationary field magnet frame provided with stationary main polar projections; stationary auxiliary projections, forming in conjunction with the armature iron, a magnetic circuit distinct from that of the main polar projections; and, a coil disposed in axial

alinement with said armature, arranged to energize said 10 auxiliary polar projections, substantially as set forth.

In testimony whereof, I have hereunto signed my name, at Philadelphia in the State of Pennsylvania this 21st day of July 1906.

MATHIAS PFATISCHER.

Correction in Letters Patent No. 870,313.

It is hereby certified that in Letters Patent No. 870,313, granted November 5, 1907, upon the application of Mathias Pfatischer, of Philadelphia, Pennsylvania, for an improvement in "Dynamo-Electric Machines," an error appears in the printed specification requiring correction, as follows: In line 21, page 3, the word "roll" should read *coil*; and that the said Letters Patent should be read with this correction therein that the same may conform to the record of the case in the Patent Office.

Signed and sealed this 19th day of November, A. D., 1907.

[SEAL.]

E. B. MOORE,
Commissioner of Patents.
